US0D1050426S

(12) **United States Design Patent** (10) Patent No.: **US D1,050,426 S**
(45) Date of Patent: ** Nov. 5, 2024

(54) **CONNECTOR**

(71) Applicant: **Fisher & Paykel Healthcare Limited**,
Auckland (NZ)

(72) Inventors: **Laurence Gulliver**, Auckland (NZ);
Michael Paul Ronayne, Auckland (NZ); **Charles William Douglas**
Irving, Auckland (NZ); **Mark Thomas**
O'Connor, Auckland (NZ)

(73) Assignee: **Fisher & Paykel Healthcare Limited**,
Auckland (NZ)

(**) Term: **15 Years**

(21) Appl. No.: **29/804,769**

(22) Filed: **Aug. 23, 2021**

Related U.S. Application Data

(60) Continuation of application No. 29/751,537, filed on
Sep. 22, 2020, now Pat. No. Des. 928,948, which is
a continuation of application No. 29/698,190, filed on
Jul. 15, 2019, now Pat. No. Des. 899,590, which is a
division of application No. 29/664,553, filed on Sep.
26, 2018, now Pat. No. Des. 861,162, which is a
continuation of application No. 29/534,250, filed on
Jul. 27, 2015, now Pat. No. Des. 834,712, which is a
division of application No. 29/433,930, filed on Oct.

(57) **CLAIM**

The ornamental design for a connector as shown and
described.

DESCRIPTION

FIG. 1 is a front, top, and side perspective view of a
connector, the opposite side being a mirror image.

FIG. 2 is a back, top, and side perspective view thereof.

FIG. 3 is a top view thereof, the bottom being a mirror
image.

FIG. 4 is a side view thereof, the opposite side being a mirror
image.

FIG. 5 is a front view thereof; and,

FIG. 6 is a back view thereof.

The portions of the connector shown in broken line form no
part of the claimed design.

1 Claim, 3 Drawing Sheets

Related U.S. Application Data

5, 2012, now Pat. No. Des. 735,326, which is a continuation of application No. 29/429,467, filed on Aug. 10, 2012, now Pat. No. Des. 747,471.
